UNITED STATES PATENT OFFICE.

LESLIE S. UPHOFF, OF THE UNITED STATES ARMY, ASSIGNOR TO THE SECRETARY OF WAR OF THE UNITED STATES OF AMERICA, TRUSTEE.

SYSTEM OF VOLTAGE CONTROL.

Application filed June 26, 1919. Serial No. 306,996.

(FILED UNDER THE ACT OF MARCH 3, 1883, 22 STAT. L., 625.)

To all whom it may concern:

Be it known that I, LESLIE S. UPHOFF, a citizen of the United States, stationed at Washington, D. C., have invented an Improvement in System of Voltage Control, of which the following is a specification.

The invention described herein may be used by the Government, or any of its officers or employees in prosecution of work for the Government, or by any other person in the United States, without payment of any royalty thereon.

The subject of this invention is a system of voltage control adapted especially for use with X-ray machines.

It has been customary to determine the voltage in an X-ray machine by means of measurement of the spark-gap. This is an inaccurate and unsatisfactory method and 20 is the cause of many failures in taking pictures as the spark terminals are often drawn apart after the spark has started, thereby drawing the spark with them and giving an incorrect idea of the voltage.

To secure the best results a uniform spark-gap should be maintained and the voltage and current accurately known in order that the penetrability of the rays and the time of exposure may be determined. This is necessary because the penetrability of the rays 30 depends on the voltage supplied and the number of rays controls the time of exposure.

A change in voltage due to ohmic resistance of the circuit is experienced for every change of current, viz., the number of milliamperes flowing through the tube, this change must be compensated for and the present system is devised to provide a ready and efficient method for compensating for such change.

This system of control is provided for by placing a voltmeter across the main line; connecting a line voltage adjuster, in the nature of a switch, between the main line and the auto transformer to maintain the volts per turn in the auto transformer constant and connecting a secondary voltage compensator between the auto transformer and the primary of the high tension transformer.

Of late years a self-rectifying tube has

come into use for X-ray machines, thus doing away with the rotary rectifier, so that a direct circuit leads from the transformer to the tube. The present system of control is adapted to care for an X-ray machine equipped with such a self-rectifying tube.

The present invention, therefore, aims to provide a system of voltage control for X-ray machines without the use of a spark gap or kilovoltmeter.

With these objects in view, the invention resides in the combination and arrangement of parts and in the details of construction hereinafter described and claimed, it being understood that changes in the precise embodiment of the invention herein disclosed can be made within the scope of what is claimed without departing from the spirit 70 of the invention.

Practical embodiments of the invention are shown in the accompanying drawings, wherein:—

Fig. 1 is a diagrammatic view of an X-ray equipment constructed in accordance with the invention;

Fig. 2 is a similar view of the alternating equipment arranged in a slightly different manner; and

Fig. 3 is a chart of an alternating current X-ray machine.

Referring to the drawings by numerals of reference:—

Referring particularly to Fig. 1, the main line is indicated at 1 and in this line is joined an autotransformer 2, from which a circuit 3 leads to the primary 4 of a step-up transformer, the secondary of which is indicated at 5. The secondary 5 is connected 90 by the line wires 6—6 with the brushes 7—7, of a rotary rectifier 8, which in turn is connected through the brushes 9—9 and circuit wires 10, 10' with the terminals of an X-ray tube 11.

The milliammeter 12 is connected in series in the circuit 10 for the purpose of determining the strength of the current furnished to the tube. One terminal 13 of the tube is a hot filament which is connected by circuit wires 14 to the secondary 15 of a transformer, the primary 16 of which is connected through line wires 17 and 17' with a suitable source of current supply. A va-

riable resistance 18, is provided in the line wire 17 and serves to regulate the current supplied to the filament so as to control the current passing through the tube.

5 For the purpose of the present invention, a volt meter 19 is connected in parallel in the main line 1, and a switch 20, adapted to selectively engage contacts 21, which are joined by suitable taps 22 to selected convolutions of the autotransformer 2, is interposed between one branch of the main line and the autotransformer for the purpose of maintaining the volts per turn in the autotransformer constant.

15 A series of taps 23 are connected to selected convolutions of the autotransformer 2 and are provided with contacts 24, positioned to be selectively engaged by a switch 25, which switch is positioned in and forms 20 a part of one branch or line of the circuit 3. These taps 23 are so positioned on the autotransformer 2 as to cause a variation in voltage equivalent to a selected variation in spark gap, say $\frac{1}{4}$ ". A switch 26 may also 25 be provided in this branch of the circuit 3, for the purpose of opening or closing the circuit as desired. At that end of the autotransformer remote from the end at which the taps 23 are connected, taps 27 are connected to the convolutions of the autotransformer and their positions are so selected as 30 to provide proper compensation for voltage variation caused by selected changes in the milli-amperes of current furnished. These 35 taps terminate in contacts which are positioned to be selectively engaged by a switch 29, which switch is interposed in the other branch of the circuit 3. This branch 40 of the circuit 3 is provided with a gap bridged by a fixed resistance 30 across which the current may be short-circuited by a switch 31 which closes the gap.

45 Referring to Figure 2, it will be seen that the taps 27 are connected to the convolutions of the primary 4 of the transformer instead of being connected to the convolutions of the autotransformer 2. In all other respects the arrangement of the system is the same and its operation is that hereinbefore 50 described in respect to Figure 1.

The operation of the system as applied to alternating current device is as follows:—

55 In making radiographs the operator uses such a combination of current and voltage in connection with the X-ray tube as experience and practice has shown to be most suitable for the size of the body to be radiographed and the nature of the work. It is necessary, therefore, in doing general radiographic work to adjust the X-ray machine for various combinations of current and voltage from time to time. Suppose an operator decided, because of the nature of the body to be radiographed, to use 30 milli- 60 amperes and a voltage equivalent to a 5"

gap (between fairly blunt points). In using a machine equipped with the system of voltage control described herein he would proceed as follows:

65 After noting the reading of the voltmeter 19 he would place switch 20 according to the voltmeter reading so as to make the volts per turn on the auto-transformer a certain predetermined amount at which the machine was calibrated. He would then set switch 29 at the point marked 30 M. A. and switch 25 at the point marked 5". He would then close switch 26 so as to apply the high voltage to the tube and adjust resistance 18 until the milliammeter 12 indicates 30 milliamperes. Since the machine is so calibrated that a voltage corresponding to a 5" gap is obtained when switch 25 is set on the point marked 5" and when the current indicated by milliammeter 12 corresponds to the setting 80 of switch 29, the voltage actually obtained would be that which was desired, i. e. a 5" gap voltage. Switch 29 is so arranged that the voltage drop caused by a given increment of current through the tube is exactly 85 or approximately counterbalanced by an increase of voltage applied to the primary of the high tension transformer from the line side of the autotransformer. The voltage 90 across the tube must, therefore, always be as indicated by switch 25 provided the current through the tube is of the value indicated by switch 29. When switch 29 is arranged to counterbalance the voltage drop 95 caused by given increments of current when switch 25 is at a given setting, it is also correct for every other setting of switch 25 for 100 the following reasons:

105 For an auto-transformer having a small copper loss the present voltage drop is practically the same for any setting of switch 25. This is a well known characteristic of auto-transformers. Therefore, if switch 29 is calibrated to compensate correctly for one setting of switch 25 it will compensate correctly for every other setting.

110 Having described my invention, what I claim as new and desire to secure by Letters Patent, is:—

115 1. A system of voltage control, including a main line, a voltmeter in the main line, an auto-transformer in the main line, means for selectively varying the number of turns of the auto-transformer connected in the main line, a transformer connected to the auto-transformer, means for selectively varying the milliamperes of current supplied from the auto-transformer to the transformer, means graduated in terms of spark gap for selectively varying the voltage supply from the auto-transformer to the transformer, and a rectifier connected to the transformer.

120 2. A system of voltage control, including a main line, a voltmeter in the main line, an auto-transformer, means for selectively vary-

ing the number of turns of the auto-transformer connected in the main line, a transformer connected to the auto-transformer, means for selectively varying the milli-
5 amperes of current supplied from the auto-transformer to the transformer, means for selectively varying the voltage supply from the auto-transformer to the transformer and means for adjusting the current supplied from the transformer to agree with the milli-
10 amperes of current supplied from the auto-transformer to the transformer.

LESLIE S. UPHOFF.
